UNITED STATES PATENT OFFICE.

HARRY MILES THOMPSON, OF WASHINGTON, PENNSYLVANIA.

MUFFLE-LEER.

1,281,713.

Specification of Letters Patent. Patented Oct. 15, 1918.

Application filed June 1, 1918. Serial No. 237,711.

To all whom it may concern:

Be it known that I, HARRY M. THOMPSON, a citizen of the United States of America, and resident of Washington, county of Washington, and State of Pennsylvania, have invented certain new and useful Improvements in Muffle-Leers, of which the following is a specification.

This invention relates broadly to annealing furnaces or leers for glassware, and more particularly to a leer of the continuous muffle type.

The primary object of the invention is to provide a muffle leer adapted for the use 15 of raw or clean producer gas, natural gas, or oil, as fuel, and embodying in the fire-box end thereof readily repairable and renewable means whereby the leer chamber is separated from the combustion, or muffle, 20 chamber and whereby ready radiation and uniform distribution of heat throughout the leer chamber is facilitated.

A further object is to provide a leer of the character mentioned in which the burners employed, whether the fuel used be producer gas, or oil or natural gas, are located in positions which are conveniently accessible.

Another object is to provide, in a leer of 30 the character mentioned and in association with means for introducing raw producer gas, a regeneration chamber in which such gas is preheated. With these and other important objects in view, the invention consists in the structural features and combinations which will hereinafter be set out, reference being had to the accompanying drawings, in which—

Figure 1 is an approximately central longitudinal section of the hot, or fire-box, end of a leer constructed in accordance with my invention;

Fig. 2 is a horizontal section on line 2—2, Fig. 1;

Fig. 3 is a transverse section on line 3—3, Fig. 1; and—

Fig. 4 is an enlarged section on line 4—4, Fig. 3.

Referring to said drawings, 1 indicates 50 the front end-wall, 2 the opposite side-walls, and 3 the arch or crown of the fire-box end of an annealing furnace or leer for glassware. Extending longitudinally through the leer is the leer-chamber 4 which is to 55 be heated, said chamber having in the bottom thereof the upper runway 5 upon which

travels the usual endless ware carrier 6. Located over the front end of said leer chamber 4 and beneath the crown 3 is a muffle chamber 7 within which, through combustion of the fuel gases employed, an annealing heat is generated. Overlying said muffle chamber is a flat horizontal roof composed of flat tile-plates 8 mounted upon transversely disposed structural-iron supporting 60 beams 9 which have their ends supported by lateral leer-chamber-defining walls 10 located parallel to and at a spaced distance from the outer side-walls 2. Said tile-plates have ship-lap or tongue and groove edges, 65 and are so disposed relatively that expansion and contraction thereof is permitted without the production of cracks, crevices, or fissures through which could occur leakage of products of combustion which might 70 result in contamination or discoloration of the ware in the leer chamber.

The products of combustion pass from the muffle chamber 7 downward through vertical flues 11 provided between the leer-walls 10 and the outer furnace walls 2 to and through transverse flues 12 which communicate at their inner ends with longitudinal flues 13, thence through said flues 13 to and through transverse flues 14 which communicate at their outer ends with vertical flues 15, similar to said flues 11, provided between said walls 2 and 10, thence through said flues 15 to a regeneration chamber 16 which is located over said leer-chamber 4 75 and is separated therefrom by tile-plates 8 similar to tile-plates 8 and which is also separated from the inner end of the muffle chamber 7 by a vertical division-wall 17. From said regeneration chamber 16 the 80 products of combustion pass through a rear wall 18 to a passage or flue 19 leading to the stack (not shown).

The floor of the leer chamber, which separates the latter from the flues 12, 13 and 14, 85 is composed of suitably mounted tiles, similar to the tiles 8, which are heated by the products of combustion escaping through said flues and which radiate the absorbed heat into said leer chamber. Also mounted 90 at suitable intervals in the walls 10 of the leer-chamber are other tiles 20 through which is radiated heat which passes through the vertical flues 11 and 15.

When oil, clean producer gas or natural 95 gas is used as fuel, the same is preferably introduced directly into the muffle chamber

through suitable burners (not shown) associated with burner ports 21 provided in the front end-wall 1. When raw producer gas is used, the same is mixed with air and both the gas and air are heated to a combustion-promoting degree prior to their introduction into the muffle chamber. This mixing and preheating is accomplished within the regeneration chamber 16, a conductor pipe 22 10 for gas and a similar pipe 23 for air being directed through the length of said chamber, said pipes joining at a suitable point located rearward of the division wall 17 and thence directing the mixed gas and air into the muffle chamber through an inlet passage 31 in said division wall.

The air pipe 23 preferably leads from a suitably located fan or blower (not shown), or natural draft may be employed. The gas pipe 22 leads from a vertically disposed supply pipe 24 which is mounted upon and projects downward through the wall 25 which defines the top of the flue 19 leading to the stack. Said pipe 24 has therein or associated therewith a suitable adjustable valve or damper, as 26, by means of which the passage of gas may be controlled or regulated. The said gas-conducting pipe 22 is connected to said supply pipe 24 at a point above the lower closed end 27 of the latter so that a pocket or receptacle for dust and dirt is afforded between said connection point and said closed end. A clean-out opening 28 having a suitable door-like closure 29 is provided through which access may be had to the said pocket for removing collected dust and dirt.

A suitable closure, as the damper 30, is provided whereby the opening 31 in the division wall 17 may be closed when not in use as an inlet for producer gas.

Suitably arranged door-closed clean-out openings, as 22, may be provided in the outer walls 2 to permit access to the flues 12 45 for cleaning.

Due to the employment of the flat tiles 8 and 81 arranged to form a perfectly flat plain roof for the leer chamber, increased radiation and absolutely uniform distribution of heat from one side of said chamber to the other is effected, as distinguished from the radiation and distribution obtainable when hollow tiles arranged to form an arched roof are employed. Further, said flat tiles are not so readily warped and distorted in form under the influence of the intense heat as are the commonly used hollow tiles disposed to form an arch, and, additionally, lend themselves to ready replacement or repair when injured without its being necessary to tear out and rebuild the entire floor.

Another evident advantage of the structure herein described is that which results 65 from the arrangement of the various flues

in such manner that heat is radiated into the leer chamber through its sides and bottom as well as through its roof.

The fact that the furnace is adapted for the use of any commonly-used gaseous fuel 70 is a feature of decided advantage among others which might be recited, but which will be readily recognized by those skilled in the art.

What is claimed is—

1. In a muffle leer, a leer chamber having a flat roof and a floor, both composed of plates, a muffle chamber located over the front end of said muffle leer chamber and separated therefrom by said roof, a regeneration chamber located rearward of said muffle chamber and separated therefrom by a division wall, a series of flues leading around said leer chamber from said muffle chamber to said regeneration chamber, and 85 means for conducting gas through said regeneration chamber and directing the same into said muffle chamber.

2. In a muffle leer, a leer chamber having a flat roof and a floor, both composed of 90 plates, a muffle chamber located over the front end of said muffle leer chamber and separated therefrom by said roof, a regeneration chamber located rearward of said muffle chamber and separated therefrom by 95 a division wall, a series of flues leading around said leer chamber from said muffle chamber to said regeneration chamber, and a gas-conducting pipe leading through said regeneration chamber and discharging into 100 said muffle chamber through said division wall.

3. In a muffle leer, a leer chamber having a flat roof and a floor, both composed of plates, a muffle chamber located over the 105 front end of said muffle leer chamber and separated therefrom by said roof, a regeneration chamber located rearward of said muffle chamber and separated therefrom by a division wall, a series of flues leading 110 around said leer chamber from said muffle chamber to said regeneration chamber, and a gas-conducting pipe and an air conducting pipe leading through said regeneration chamber, both of said pipes discharging 115 through said division wall into said muffle chamber.

4. In a muffle leer, a leer chamber having a flat roof and a floor, both composed of plates, a muffle chamber located over the 120 front end of said muffle leer chamber and separated therefrom by said roof, a regeneration chamber located rearward of said muffle chamber, a division wall separating said regeneration chamber from said muffle 125 chamber and having a closable passage therethrough, means for directing fuel through the front wall of said muffle chamber, a series of flues leading around said leer chamber from said muffle chamber to 130

said regeneration chamber, and gas-conducting means leading through said regeneration chamber and adapted to discharge into said muffle chamber through said closable passage.

5. A muffle leer comprising outer side walls and end walls with an overlying arch, a leer chamber, a flat roof for said chamber, said roof being composed of tile-plates, a muffle chamber having fuel inlet openings in the walls thereof, said muffle chamber being located over the front end of said leer chamber, a regeneration chamber located rearward of said muffle chamber, a division wall having a closable passage therethrough separating said regeneration chamber from said muffle chamber, a floor for said leer chamber, flues located beneath said floor, flues in said side walls providing communication between said muffle chamber and the receiving ends of said under-floor flues, flues in said walls providing communication between the discharge ends of said under-floor flues and said regeneration chamber, and means for conducting gas through said regeneration chamber and discharging into said muffle chamber through the passage in said division wall.

6. A muffle leer comprising outer side walls and end walls with an overlying arch, a leer chamber, a flat roof for said chamber, said roof being composed of tile-plates, a muffle chamber having fuel inlet openings in the walls thereof, said muffle chamber being located over the front end of said leer chamber, a regeneration chamber located rearward of said muffle chamber, a division wall having a closable passage therethrough separating said regeneration chamber from said muffle chamber, a floor for said leer chamber, flues located beneath said floor, flues in said side walls providing communication between said muffle chamber and the receiving ends of said under-floor flues, flues in said walls providing communication between the discharge ends of said under-floor flues and said regeneration chamber, gas-conducting means wherein gas is preheated located within said regeneration chamber and discharging into said muffle chamber through the passage in said division wall, and means for mixing air with said gas.

7. A muffle leer comprising outer side walls and end walls with an overlying arch, a leer chamber, a flat roof for said chamber, said roof being composed of tile-plates, a muffle chamber having fuel inlet openings in

the walls thereof, said muffle chamber being located over the front end of said leer chamber, a regeneration chamber located rearward of said muffle chamber, a division wall having a closable passage therethrough separating said regeneration chamber from said muffle chamber, a floor for said leer chamber, flues located beneath said floor, flues in said side walls providing communication between said muffle chamber and the receiving ends of said under-floor flues, flues in said walls providing communication between the discharge ends of said under-floor flues and said regeneration chamber, gas-conducting means wherein gas is preheated located within said regeneration chamber and discharging into said muffle chamber through the passage in said division wall, and means for conducting air through said regeneration chamber and mixing the same with the gas prior to its discharge into said muffle chamber.

8. A muffle leer comprising outer side walls and end walls with an overlying arch, a leer chamber, a flat roof for said chamber, said roof being composed of tile-plates, a muffle chamber having fuel inlet openings in the walls thereof, said muffle chamber being located over the front end of said leer chamber, a regeneration chamber located rearward of said muffle chamber, a division wall having a closable passage therethrough separating said regeneration chamber from said muffle chamber, a floor for said leer chamber, flues located beneath said floor, flues in said side walls providing communication between said muffle chamber and the receiving ends of said under-floor flues, flues in said walls providing communication between the discharge ends of said under-floor flues and said regeneration chamber, a vertical gas supply pipe having a lower closed end located outside said regeneration chamber, a gas-conducting pipe connected to said supply pipe above said closed end, said conducting pipe being extended through said regeneration chamber and discharging into said muffle chamber through the passage in said division wall, and means permitting access to the lower end of said supply pipe.

In testimony whereof, I affix my signature in presence of two subscribing witnesses.

HARRY MILES THOMPSON.
